ASH TRAY

Frank J. Curran, 3250 N. Highland Ave.,
Downers Grove, Ill. 60515

Filed July 18, 1968, Ser. No. 12,811

Term of patent 14 years

Int. Cl. D27—03

U.S. Cl. D85—2

I claim:

The ornamental design for an ash tray, as shown.
